UNITED STATES PATENT OFFICE.

GUSTAV GROSS, OF BRESLAU, GERMANY.

SPARK-ARRESTER.

1,070,800.

Specification of Letters Patent. Patented Aug. 19, 1913.

Application filed September 3, 1912. Serial No. 718,374.

To all whom it may concern:

Be it known that I, GUSTAV Gross, doctor of philosophy, chemist, a subject of the German Emperor, and resident of Breslau, 5 Silesia, Germany, have invented new and useful Improvements in Spark-Arresters, of which the following is a specification.

My invention relates to improvements in spark arresters, and it consists in the constructions and combinations herein described and claimed.

The object of my invention is to provide an improved spark arrester, especially adapted for use with locomotives, which will 15 act effectively to separate all heavy matters, such as sparks and cinders from the flue gases.

In the accompanying drawings forming a part of this application in which similar 20 reference symbols indicate corresponding parts in the several views:—Figure 1 is a vertical axial section, illustrating one embodiment of my invention; and Fig. 2 is a section on the line A—A of Fig. 1.

25 Referring to the drawings, *b* indicates a vertical cylindrical flue for receiving the gaseous products of combustion from a chamber, such as the smoke box *a* of a locomotive; said flue being provided with a flaring discharge end *b*¹. A cylindrical core *h* is supported by brackets *h*¹ axially within the flue *b* and terminates in a flaring upper head within the flaring discharge end of 30 said flue; said core being provided with a 35 tapered lower end within the entrance end of the flue.

A hollow ring *i* is supported at the entrance end of the flue *b* and provided with an annular series of nozzles about the adjacent tapered end of the central core *h*; said nozzles being inclined to the axis of the flue for directing jets of fluid spirally through the latter. A suitable fluid, such as steam or compressed air, is applied under pressure to 45 the hollow jet ring *i* by a pipe *h*. A pair of pipes *c* are shown discharging spirally within the flue *b* for directing additional fluid jets with a whirling motion through the air.

An outer casing, comprising inclined 50 walls *d*¹ and *d*² and the lower cylindrical wall, is supported about the flue *b* to provide an outer chamber for receiving the heavy sparks and cinders separated from the flue gases; said casing being provided 55 with a discharging cylindrical conduit *b*²

which extends concentrically within the flaring discharge end of the flue *b*¹ at a point above the central core *h*. A plate *e* is secured spirally on the walls of said outer chamber for directing the sparks and cinders deposited thereon into the lower cylindrical portion *f* of said chamber; said plate being of less width than the outer chamber to provide a space *e*¹ about the flue, for permitting a whirling action of the gases.

A discharge spout *g* for the cinders leads from the lower end of the spiral plate *e*, to provide convenient means for discharging the cinders at any desired point.

From the above description, it will be 70 clear that my invention provides a simple and compact construction adapted to efficiently separate all sparks and heavy matters from the flue gases, without interfering with the draft of the latter.

I have illustrated and described preferred 75 and satisfactory constructions, but changes could be made within the spirit and scope of my invention.

I claim:—

1. In a spark arrester, the combination of a cylindrical flue provided with a flaring discharge end, a central core extending axially therethrough, means for directing jets of fluid spirally through said flue, a casing supported about said flue to provide an outer chamber, and a cylindrical discharge conduit extending from said casing concentrically within the flaring end of said flue.

2. In a spark arrester, the combination of 90 a cylindrical flue provided with a flaring discharge end, a central core extending axially through said flue and provided with a flaring head within the flaring discharge end of the latter, means for directing jets of fluid spirally through said flue, a casing supported about said flue to provide an outer chamber, and a cylindrical discharge conduit extending from said casing concentrically within the flaring end of said flue and 95 terminating above said central core.

3. In a spark arrester, the combination of a cylindrical flue provided with a flaring discharge end, a central core extending axially therethrough, means for directing jets 105 of fluid spirally through said flue, a casing supported about said flue to provide an outer chamber, a cylindrical discharge conduit extending from said casing concentrically within the flaring end of said flue, 110

and a spiral plate supported within such outer chamber and extending across a portion only of the width of the latter.

4. In a spark arrester, the combination 5 of a cylindrical flue provided with a flaring discharge end, a central core extending axially through said flue and provided with a tapered end within the entrance end of the latter, an annular series of inclined nozzles 10 surrounding such tapered core end, a casing supported about said flue to provide an outer

chamber, and a cylindrical discharge conduit extending from said casing concentrically within the flaring end of said flue.

In testimony that I claim the foregoing 15 as my invention, I have signed my name in presence of two witnesses, this twenty-third day of August, 1912.

GUSTAV GROSS.
